UNITED STATES PATENT OFFICE.

JAMES F. McELROY, OF ALBANY, NEW YORK.

DESIGN FOR A RADIATOR.

SPECIFICATION forming part of Design No. 23,630, dated September 4, 1894.

Application filed June 9, 1894. Serial No. 514,102. Term of patent 14 years.

To all whom it may concern:

Be it known that I, JAMES F. McELROY, a citizen of the United States, residing at the city and county of Albany, State of New York, have invented a new and original Design for Radiators, of which the following is a specification, reference being had to the accompanying drawing, forming a part thereof.

The figure is a perspective view.

The leading feature of my design consists in a radiator of the shape shown provided with the curved plate A presenting a convex surface to the front of the radiator. Extending along the front of the radiator above the

plate A, is a series of openings B, the plate C 15 on the top of the radiator extending the whole length, together with a series of openings D arranged at the bottom below the plate A, which lower end of the plate A is slightly raised above the floor. 20

What I claim as my invention, and desire to secure by Letters Patent, is—

The design for a radiator as herein shown and described.

JAMES F. McELROY.
